STITCH-CUTTING MACHINE

Filed Jan. 17, 1939

UNITED STATES PATENT OFFICE

2,180,414

STITCH-CUTTING MACHINE

George Hazelton, Leicester, England, assignor to
United Shoe Machinery Corporation, Borough
of Flemington, N. J., a corporation of New Jersey

Application January 17, 1939, Serial No. 251,379
In Great Britain February 2, 1938

8 Claims.

(Cl. 12—1)

This invention relates to stitch-cutting machines and is illustrated as embodied in a machine for severing stitches securing the heel end of an attached outsole to a shoe.

5 In the manufacture of McKay or lockstitch shoes, for example, it is common practice for the operator to sever sole-attaching stitches which extend rearward of the heel-breast line of the sole of the shoe in order that a crease plate or a cutting bed of a fitting machine for trimming the heel end of the sole for the reception of a heel may be interposed between the bottom of the shoe and the portions of the sole extending rearward of said heel-breast line. To sever the stitches by the use of a hand knife requires considerable time and is subject to the objection that the operator tends to cut stitches extending a considerable distance forward of the heel-breast line.

20 In accordance with a feature of this invention, there is provided a machine comprising a plate constructed and arranged to be interposed between the heel end of an attached sole of a shoe and the bottom of the shoe, cutting means, mechanism for causing said cutting means to vibrate back and forth, and means for causing the plate normally to mask the cutting means, the plate being movable in response to pressure exerted against the same by uncut stitches securing the heel end of the sole to the shoe upper thereby rendering said cutting means operative for the purpose of severing said stitches.

25 The operator presents the shoe heel-end first and bottom-side up to the machine, the rear end of the sole sliding over the top of the masking plate and the remainder of the heel end of the shoe passing beneath said plate. When sole-attaching stitches extending rearward of the heel-breast line of the shoe engage the front edge of the masking plate, they move the plate rearward, thereby exposing the cutting edges of knives 30 which constitute the cutting means and which are vibrated over the upper surface of the plate, to cut the sole-attaching stitches. In order to limit the forward extent to which the stitches are cut the machine is provided with a back gage which 35 may be set in different adjusted positions. The operator can quickly present the shoe to the stitch-cutting machine, which is preferably mounted upon the same base as a fitting machine, the arrangement being such that at one handling of the shoe the operator cuts the sole-attaching stitches as desired and then presents the shoe to the fitting machine.

40 The various features of the invention will be understood and appreciated from the following

detailed description read in connection with the accompanying drawing, in which

Figs. 1 and 2 are front and plan views, respectively, partly in section and partly broken away, of an illustrative machine;

Fig. 3 is a section on line III—III of Fig. 1;

Fig. 4 is an enlarged plan view showing the stitch-cutting knives in their unmasked operative positions, the shoe being operated upon having been moved rearward against the back gage; and

Fig. 5 is a perspective view of the heel end of the shoe, the rear sole-attaching stitches of which are to be severed by the above machine.

The illustrated machine is described with reference to cutting stitches 20 (Figs. 2, 4 and 5) securing the heel end of a sole 22 to a shoe 24 preparatory to trimming the sole for the reception of a heel, for example, by the fitting machine disclosed in United States Letters Patent No. 2,017,151, granted October 15, 1935, on an application filed in the names of Hazelton, James and Bacon. As above stated, in order that a cutting bed (not shown) of the above-mentioned fitting machine, or crease plates (not shown) such as used in proposed heel-seat fitting machines may be readily interposed between the bottom 26 (Fig. 5) of the shoe upper and the portion of the sole 22 extending rearward of the heel-breast line 28, it is desirable first to cut any sole-attaching stitches extending rearward of the heel-breast line. By the use of the illustrated machine the operator can quickly and effectively cut the stitches 20 extending rearward of the heel-breast line 28 of the sole without any danger of cutting stitches extending a substantial distance forward of said line.

30 Secured by screws 30 (Figs. 1 and 2) to a casting 32 is a bridge piece 34 having an arcuate guideway 36 in which two slides 38, 39 are movable. The slides 38, 39 are located side by side and are retained in the guideway by upstanding walls of the bridge piece 34 and by a cover plate 40 which is secured by screws 42 to the bridge piece.

35 Rotatably mounted in the left side of the casting 32 is a horizontal shaft 44 (Fig. 2) extending forwardly and rearwardly of the machine and having a drive pulley 46 secured to its rear end. The shaft 46 has mounted on it a pair of eccentrics 48 which are embraced by the connecting rods 50 pivoted to the left-hand portions of the respective slides 38, 39. When the shaft 44 is rotated the slides 38, 39 oscillate in the guideway 36, the angular movement of the eccentrics being such that when the rear slide 39 is at the left

limit of its stroke the forward slide 38 is at the right limit of its stroke and vice versa. Formed integral with slides 38 and 39 are downwardly projecting blocks 52, 53, respectively, each of which is split vertically and has a groove 55 (Fig. 1) for receiving a stitch-cutting knife 54. The screws 56 (Figs. 1 and 4) have their end portions in threaded relation with the inner portions of the respective blocks 52, 53 and serve to clamp the knives 54 to the blocks. Each of the knives 54 projects forwardly from its corresponding block 52, 53 and has a rounded forward end which is sharpened to a cutting edge 58 (Figs. 2 and 4). The forward portions of the knives 54 are curved laterally and lie against the upper surface 60 of an arched masking plate or slide 62 which is movable along horizontal forwardly and rearwardly extending guideways 64 formed in the casting 32. The masking plate 62 is constantly urged forward by coil springs 66 (Figs. 2 and 3) which are located in recesses 67 (Fig. 3) formed in depending portions 70 of the masking plate 62, forward movement of the masking plate being limited by stop screws 72 which may be secured in different adjusted positions to plates 74 clamped to the casting 32 by screws 76. The rear ends of the springs 66 engage retaining collars 63 (Fig. 3) formed integral with screws 65 which are threaded into plates 67 secured to the casting 32 by screws 69. The screws 65 may be secured against movement with relation to the respective plates 67 by lock nuts 71. Rearward movement of the masking plate 62 against the action of the springs 66 is limited by the engagement of adjustable stop screws 78 carried by the depending portions 70 of the masking plate 62 with the respective plates 67.

The stitch-cutting knives 54 remain in contact with the upper surface 60 of the masking plate 62 as they are oscillated or vibrated. The masking plate 62 is constantly urged by the springs 66 to the position illustrated in Fig. 2 in which its forward edge 90 is arranged slightly in advance of the cutting edges 58 of the knives 54, and may be moved rearward against the action of the springs 66 until the cutting edges 58 of the knives extend slightly forward of the edge 90 of the plate. Located between the knife-engaging portions of the surface 60 of the masking plate 62 is a slightly raised serrated face 91 which engages the heel end of the attached sole and counteracts any tendency of the same to be laterally displaced by the knives.

The shoe is moved rearward by the operator, the heel end of the attached sole of the shoe sliding over the upper surface 60 of the masking plate 62 and the remainder of the heel end of the shoe passing beneath the plate. The masking plate 62 is quite thin and has a transverse curvature corresponding to the transverse curvature of the average shoe bottom so that the plate can be readily interposed between the sole and the shoe bottom without unduly bending the sole. The plate 62 maintains its masked position ahead of the knives 54 as shown in Fig. 2 until it is engaged by the sole-attaching stitches 20 which extend rearwardly of the heel-breast line 28 of the sole, the knives oscillating transversely of the plate with their cutting edges 58 masked by the plate. When, however, a stitch to be cut is forced against the forward edge 90 of the masking plate 62, the plate is moved rearwardly along the guideways 64 by pressure of the stitch against said plate until the rounded cutting edges 58 of the knives 54 are exposed, as illus-

trated in Fig. 4, to sever the obstructing stitch, the two knives serving respectively to cut the lines of stitches at opposite sides of the sole should both lines extend rearward of the heel-breast line 28 of the sole.

In order that the sole-attaching stitches 20 shall not be cut a substantial distance forwardly of the heel-breast line 28 there is provided a back gage 92 which limits the rearward movement of the shoe. The back gage 92 may be located in a predetermined forward or rearward position in accordance with the length of a heel (not shown) which is to be attached to the shoe, and is measured in a heel gage (not shown). The mechanism for locating the back gage 92 in different adjusted positions is similar to corresponding mechanism disclosed in United States Letters Patent No. 1,840,030, granted January 5, 1932, in the names of Gouldbourn, Ricks and Barclay, and need not be further described herein. When cutting sole-attaching stitches preparatory to trimming the sole by the machine disclosed in said United States Letters Patent No. 2,017,151 it is customary to set the back gage 92 so that the stitch-severing operation ends approximately one-eighth of an inch in advance of the heel-breast line 28 of the sole.

After the shoe has been moved rearwardly against the back gage 92 it is removed from the machine, the masking plate 62 being moved forwardly in its guideways 64 by the springs 66 until it is stopped by the screws 72.

Having described my invention, what I claim as new and desire to secure by Letters Patent of the United States is:

1. A stitch-cutting machine having, in combination, a plate constructed and arranged to be interposed between the heel end of an attached sole of a shoe and the bottom of the shoe, cutting means, mechanism for causing said cutting means to vibrate back and forth, and means for causing the plate normally to mask said cutting means, said plate being movable in response to pressure exerted against the same by uncut stitches securing the heel end of the sole to the shoe upper thereby rendering said cutting means operative to sever said stitches.

2. A stitch-cutting machine having, in combination, a plate constructed and arranged to be interposed between the heel end of an attached sole and a shoe and the bottom of the shoe, a pair of knives having cutting edges, means for moving the knives in predetermined paths, and means for causing the plate normally to mask their knives, said plate being movable in response to pressure exerted against the same by stitches securing the heel end of the sole to the shoe upper thereby rendering the knives operative to cut said stitches.

3. A stitch-cutting machine having, in combination, a plate constructed and arranged to be interposed between the heel end of an attached sole of a shoe and the bottom of the shoe, stitch-cutting knives, means for continuously moving said knives in opposite directions along and widthwise of the plate, a back gage, and means for causing the plate normally to mask the knives, said plate being movable toward the back gage when engaged by stitches securing the heel end of the sole to the shoe upper in order to render said knives operative to cut said stitches until movement of the shoe is stopped by engagement of the shoe with the back gage.

4. A stitch-cutting machine having, in combination, an arched plate which has a thin front

- edge and is constructed and arranged to be interposed between the heel end of an attached sole of a shoe and the bottom of the shoe, knives having rounded cutting edges which are in engagement with the plate and are normally located immediately rearward of the front edge of the plate, and means for oscillating the knives transversely of the plate, said plate being movable lengthwise when engaged by stitches securing the heel end of the sole to the shoe upper to move said front edge of the plate rearward of said cutting edges thereby rendering the knives operative to cut said stitches.
5. A stitch-cutting machine having, in combination, an arched plate having a thin front edge, said plate being constructed and arranged to be interposed between the heel end of an attached sole of a shoe and the bottom of the shoe, a pair of knives having cutting edges, means for 10 oscillating the knives over the plate with their respective cutting edges in engagement with the plate and normally positioned just rearward of the front edge of the plate, stops, resilient means for normally forcing the plate against said stops 15 thereby causing said cutting edges of the knives to be normally masked by the plate, and guideways for directing the plate in a predetermined path against the action of said resilient means when stitches by which the heel end of the sole 20 is attached to the shoe engage the front edge of the plate, thereby causing the knives to project forwardly of the plate and to cut said sole-attaching stitches.
- 25 6. A machine for cutting stitches by which the heel end of a sole is secured to a shoe having, in combination, a slide having a thin front edge, resilient means for constantly urging the slide forward, an adjustable stop for limiting forward movement of the slide, a pair of knives having 30 cutting edges which are positioned adjacent to the slide and which are masked by the front edge of the slide when the latter is in engagement with said stop, means for oscillating the knives widthwise of the slide, and a gage for stopping the shoe in a predetermined position in the machine.
- 35 7. A stitch-cutting machine having, in combination, a plate having a thin front edge, a back gage, a pair of knives having cutting edges which are normally masked by the front edge of said plate, and means for oscillating the knives widthwise of the plate, said plate being constructed and arranged to be interposed between the heel end of an attached sole of a shoe and the bottom of the shoe by forcing the shoe against the plate 15 until further rearward movement of the shoe is prevented by the back gage, said plate being movable toward the back gage when lines of stitches extending rearward of the heel-breast line of the shoe are forced against the plate thereby rendering said knives operative to cut said stitches.
- 40 8. A stitch-cutting machine having, in combination, a thin plate constructed and arranged to be interposed between the heel end of an attached sole of a shoe and the bottom of the shoe, 20 a pair of knives having cutting edges, means for oscillating the knives over the plate, means for causing the plate normally to mask the knives, said plate being constructed and arranged to be moved when engaged by stitches attaching the 25 heel end of the sole to the shoe in order to render the knives operative for the purpose of cutting said stitches, means associated with the plate for reducing any tendency of the heel end of the sole upon the plate to shift laterally, and means for 30 limiting movement of the shoe with relation to the knives to insure against the stitches being cut too far forward.

GEORGE HAZELTON. 40

CERTIFICATE OF CORRECTION.

Patent No. 2,180,414.

November 21, 1939.

GEORGE HAZELTON.

It is hereby certified that error appears in the printed specification of the above numbered patent requiring correction as follows: Page 2, second column, line 29, for the word "bank" read --back--; line 51, claim 2, for "and" after "sole" read --of--; line 55, same claim, for "their" read --the--; and that the said Letters Patent should be read with this correction therein that the same may conform to the record of the case in the Patent Office.

Signed and sealed this 6th day of August, A. D. 1940.

Henry Van Arsdale,

Acting Commissioner of Patents.
